UNITED STATES PATENT OFFICE.

DANIEL WERTZ, OF TOLEDO, OHIO, ASSIGNOR OF ONE-HALF TO JOHN F. FLOWERS, OF TOLEDO, OHIO.

GARMENT-SUPPORTER.

No. 926,916.

Specification of Letters Patent.

Patented July 6, 1909.

Application filed March 2, 1909. Serial No. 480,913.

To all whom it may concern:

Be it known that I, DANIEL WERTZ, a citizen of the United States, residing at Toledo, in the county of Lucas and State of Ohio, 5 have invented a new and useful Improvement in Garment-Supporters, of which the following is a specification.

My invention relates to a garment supporter, and has for its object to provide a 10 simple, convenient and reliable device of the kind whereby hose and other articles of underwear may be securely supported by garters, suspenders and the like. I accomplish these objects by the construction and combination of parts as hereinafter described and 15 illustrated in the drawings, in which—

Figure 1 is a side view of a supporter constructed in accordance with my invention, unattached. Fig. 2 is a similar view showing 20 the holder of the supporter attached to a garment, partly broken away. Fig. 3 is an edge view of the supporter as shown in Fig. 1. Fig. 4 is a reverse view of Fig. 2, and Fig. 5 is an edge view of Fig. 4.

25 In the drawings, 1 designates a bail, formed of a piece of wire having equal end portions bent slightly converging, in the same plane to form the arms 2 extending from a central portion 3 of suitable length to 30 have attached thereto flatwise the full width of a garter or suspender, when looped around the portion 3. The free end portions of the arms 2 are flattened to form parallel ears 4 which are perforated in alinement.

35 In the perforations of the ears 4 is pivoted the holder 5, which is preferably formed of a piece of wire of suitable length, having its central portion bent to form a circular or oval loop 6. The end portions are then first 40 twisted around one another to form a neck 7 and then bent in opposite out-curves 8, together forming an open U shaped portion 9 extending opposite to the loop 6 from the neck 7, in the same plane. The free end 45 portions 10 of the U shaped portion 9 are then bent outward in alinement and pivoted in the perforations of the ears 4 of the bail. The ends of the pivots 10 being then upset, the holder 5 is secured against detachment

from the bail 1, which completes the supporter.

To attach the supporter to a stocking or other garment, the holder 5 is placed against the inner side of the top portion of the garment and then turned on its pivot outward 55 and upward through the bail 1, and then downward to its normal pendent position, drawing with it a portion of the fabric as shown in Figs. 2, 4 and 5.

In turning the holder down the fabric is 60 drawn downward into the U shaped portion 9 of the holder below the pivot 10, whereby a pull upward on the bail tightens the grip of the holder 5 on the fabric, without producing any tendency to reverse the movement of the 65 bail to release the fabric. The supporter thus constructed and attached provides a strong and secure hold on the garment not liable to become loosened, and the increased area of the fabric engaged by the holder 70 prevents injury thereto.

While the form of the holder 5 shown is preferred, it is manifest that it may be varied without departure from the principle of its operation and attachment, which consists 75 in its complete revolvability through the bail from a pendent position to a pendent position, and its adaptability to carry with it a portion of the fabric, which is thereby drawn through the bail and over the holder below 80 its pivotal attachment to the bail, and I therefore do not limit myself to a holder of the exact form of construction shown and described.

What I claim to be new is—

1. In a garment supporter, the combination of a bail, and a holder comprising a body portion having diverging arms, said arms being pivotally connected at their outer end portions to the end portions of the bail, and 90 adapted to normally suspend the holder below the bail, and said holder being adapted to be completely revolved from and to such pendent position in either direction through the bail, substantially as and for the purpose 95 set forth.

2. In a garment supporter, the combination of a bail, and a holder comprising a loop

having diverging arms, said arms being pivotally connected at their outer end portions to the end portions of the bail, and adapted to normally suspend the loop below the bail, and said holder being adapted to be completely revolved from and to such pendent position in either direction through the bail, substantially as set forth.

In witness whereof I have hereunto signed my name in the presence of two subscribing ¹⁰ witnesses, this 23rd day of February, 1909.

DANIEL WERTZ.

In presence of—

A. D. STEWART,
M. S. SMITH.
